UNITED STATES PATENT OFFICE.

RUSSEL S. BARNUM, OF CHICAGO, ILLINOIS.

CLAMPING DEVICE FOR SEWING-MACHINE ATTACHMENTS.

SPECIFICATION forming part of Letters Patent No. 267,992, dated November 28, 1882.

Application filed September 1, 1881. (No model.)

To all whom it may concern:

Be it known that I, RUSSEL S. BARNUM, residing at Chicago, in the county of Cook and State of Illinois, and a citizen of the United States, have invented new and useful Improvements in Clamping Devices, of which the following is a full description, reference being had to the accompanying drawings, in which—

Figures 1 and 2 are a side elevation and a top or plan view, respectively, showing the clamp applied to an arm or support having a straight body. Figs. 3 and 4 are a side elevation and a top or plan view, respectively, showing the clamp applied to an arm or support, the carrying portion of which depends from the portion having the clamp. Figs. 5 and 6 are a top or plan view and a side elevation, respectively, showing the clamp applied to an arm or support provided with a cutting-edge, so as to act as a thread-cutter.

The object of this invention is to construct a cheap, simple, and reliable clamping device, by means of which the attachment of one device to another can be readily and quickly made, and when made such attachment will be very strong and firm, and at the same time easily unclamped to permit of removal. The device is primarily designed to be used in places where the attachment cannot be readily made without removing some portion or part in order to secure some other device in position; but it can be used in other places, and can be applied to various purposes where it is desirable to have a quick and easy form or mode of attachment.

The nature of the invention consists in providing the device or part to be attached with a notch or recess adapted to receive the rod, bar, or other device to which the attachment is to be made, and act in conjunction with a set-screw to securely fasten or unite the parts together, the head of the set-screw acting to draw the two devices in contact with each other.

In the drawings three different forms of constructing and applying the clamping devices are shown; but such devices can be applied to other forms of devices than those shown, such devices in each instance to have a receiving notch or recess with which the head of a set-screw coacts.

In the drawings, A represents an arm or support, the body of which may be formed as shown, or of any other suitable form adapted to furnish a support or means of attachment. One end of this arm or support is provided with a recess, a, semicircular in form, and the extreme point or end a' of the body A is made to project beyond the face of the support on the opposite side of the opening or recess a, as shown in Fig. 2, and this face of the body receives the clamping-screw, the shank of which enters a screw-threaded opening formed in the body in proximity to the opening a, and in such relation thereto as that the head of the screw will project partly over the opening. The screw b may be of the form shown, having its head provided with a notch for the reception of a screw-driver; or such head may be formed like an ordinary thumb-screw, the inner face of the head being so formed as that it will bite or impinge on the face of the rod, bar, or other device which enters the opening a. The opening a is to be formed to conform to and receive the rod, bar, or other device to which the arm or support A is to be attached.

To apply the arm or support A and secure it in place, the clamping-screw b is withdrawn sufficiently far to allow the arm, bar, or other device to enter the recess a, when by screwing the clamp-screw down and bringing its head in contact with the face of the rod, bar, or other device, and causing it to bite thereon, such action will draw the portion of the arm or support A around the recess or notch a in close contact with the face of the rod, bar, or other device in the recess a.

In Figs. 3 and 4 the set-screw is located in a screw-threaded opening formed in the head a'' on the outer end of the body or support, and the point or projecting portion a' of the recess, which coacts with the head of the set-screw, is located on the opposite side of the recess from that shown in Fig. 2, such change in location being necessitated by the location of the clamping-screw b. The head or support A (shown in these Figs. 3 and 4) is provided with a side arm or extension, A', to the end of which may be attached any device which may be desired.

In Figs. 5 and 6 the body A is formed from a plate, and the recess a is formed by turning

the end of the plate around, so that its extreme end will form the coacting end or part *a'*, and, as shown, the body of the arm or plate *A* is provided with a blade portion, *c*. The device shown in Figs. 5 and 6 is designed for use as a thread-cutter, to be applied to the presser-foot bar of a sewing-machine, the body of such bar entering the recess *a* and the device being held thereon by the action of the clamping-screw *b*, the head of which is brought in contact with the face of the bar.

Other forms of supports or devices than the three shown can be provided with the notch or recess *a*, and projecting point *a'*, and clamping-screw *b*, arranged in such relation to each other as that the notch will receive the device to which the attachment is to be made, and the set-screw, when forced down, will firmly unite the parts together.

This clamping device furnishes a ready and quick means for making an attachment, is very simple in construction, requiring only a notch or recess, an engaging-point, and a clamping-screw. The attachment is very strong and firm, and by the use of the device named the device having the parts constituting the clamp thereon can be readily attached to or detached from the receiving device.

By using a square notch of the proper size

and a clamping-screw having a straight or flat engaging face instead of a diagonal, the attachment can be made to a square bar, rod, or other device, the same as to a round rod, bar, or other device, and by changing the form of the notch or recess to coincide with the device to which the attachment is to be made the clamping-screw and the notch can be used for producing a firm attachment.

The needle of a sewing-machine has heretofore been arranged in a recess in the needle-arm and confined in place by a screw having its head extended over the needle to bite thereon, and thus hold the same in place. Such therefore I do not claim.

What I claim as new, and desire to secure by Letters Patent, is—

A clamping device consisting of an attachable and detachable plate, having at one end a semicircular recess, *a*, forming the engaging point *a'* at one side thereof, and a set-screw attached to said plate and having its head extending partly over the recess to bind against a rod or other device on which the plate can be adjusted, substantially as described.

RUSSEL S. BARNUM.
